JOHN B. HADAWAY, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

TACK-PULLING MACHINE.

1,016,328.

Specification of Letters Patent.

Patented Feb. 6, 1912.

Application filed April 14, 1909. Serial No. 489,853.

To all whom it may concern:

Be it known that I, JOHN B. HADAWAY, a citizen of the United States, residing at Swampscott, in the county of Essex and State of Massachusetts, have invented certain new and useful Improvements in Tack-Pulling Machines; and I do hereby declare the following to be a full, clear, and exact description of the invention, such as will enable others skilled in the art to which it appertains to make and use the same.

The invention relates to machines for pulling tacks from lasted shoes.

The object of the invention is to improve the construction and mode of operation of that class of tack pulling machines in which the tacks are acted upon and extracted by one or more tack pulling blades arranged at the periphery of a rotary tack pulling tool or wheel.

As heretofore constructed, the tack pulling tools or wheels of this type of machine have usually been provided with peripheral ribs or rims at one or both ends of the blades which form guards against which the work may be pressed in presenting the shoe in position for the pulling of the tacks by the blades. These guard rims rotate with the blades, and by reason of their frictional engagement with the work, tend to continually move the work in the direction of their rotation. This tendency is especially pronounced in case a tool of this character is employed for pulling sole tacks which are driven in until their heads are substantially flush with the surface of the sole. In extracting these sole tacks, the sole of the shoe is pressed forcibly against the guard rim or rims, so that the surface of the sole at the point where the tack is located intersects or cuts across the path of the blades. By reason of the comparatively heavy pressure of the sole against the rapidly rotating guard rim or rims at this time, there is an increased tendency for the rims to move the work in the direction of their rotation. It is necessary, therefore, for the operator not only to hold the shoe firmly against the action of the tack pulling blades so that they may act efficiently to wipe the tack out of the sole, but he must also hold the shoe against the moving action of the rotary rim or rims in order that the shoe may not be moved so as to carry the tack out of proper relation to the rotating blades.

It is one object of the invention to avoid the objectionable action of the guard or guards, so that the tacks may be more readily and accurately positioned with relation to the path of the rotary blades, and with less exertion on the part of the operator.

To this end, one feature of the invention contemplates the provision in a tack pulling machine provided with a rotary tack pulling tool having a tack pulling blade at its periphery, of a work engaging guard at one or both ends of the blade which is so supported that the tack pulling tool may rotate independently of the guard or guards. In accordance with this feature of the invention in its broader aspects, the work supporting guard may be arranged at one or both ends of the tack pulling blades, and may be mounted in any suitable manner so that they will not rotate with the tack pulling blade. In the preferred and most efficient construction which has been yet devised, the work supporting guard is in the form of a disk having a circular rim, and mounted for independent rotation concentrically with the rotary tack pulling tool. This form of guard enables the shoe to be easily and conveniently moved while held in engagement with the rim, and requires the least exertion on the part of the operator, since the rim may be rotated by engagement with the sole as the shoe is advanced to bring the tacks successively into the path of the rotary blade, thus avoiding the necessity of overcoming any resistance due to the frictional engagement of the guard with the

Another feature of the invention contemplates the provision of an improved form of tack pulling blade having a chisel edge for engaging the tack, whereby the blade may be repeatedly sharpened or repaired when it becomes dull or nicked, without requiring relative adjustment of the blade and work engaging guard. In accordance with this feature of the invention, each blade of the rotary tack pulling tool is provided with a chisel edge and with a peripheral surface extending circumferentially to the rear of the edge, and formed concentric with the tool. With this construction, the front edge of the blade may be ground or cut away without varying the relation between the edge and the axis of the tool, and consequently the blade or blades may be repeatedly sharpened or repaired without requir-

ing any adjustment of the blades in order that their path of travel shall remain the same with relation to the work supporting guard or guards.

5 The several features of the invention will be readily understood from an inspection of the accompanying drawings, in which—

Figure 1 is a view showing the spindle of a tack pulling machine embodying the 10 invention in its preferred form, the tack pulling tool and work supporting guards being shown in section, and Fig. 2 is an end elevation of the spindle with the tool and guards mounted thereon.

15 In the construction shown, the spindle 1 of the tack pulling machine is provided at its end with a reduced portion 2, and the tack pulling tool 3 is secured at about the center of this reduced portion. As shown, 20 the tack pulling tool comprises a sleeve which is secured to the reduced end of the spindle by a pin 4, and is provided with two diametrically opposed tack pulling blades 5. The tack pulling blades are provided with chisel edges constructed to pass 25 under the head of a tack and to wipe or pull the tack out of the sole when the head of the tack is brought into the path of the blades. Each blade is also provided with 30 a peripheral portion 6 which extends circumferentially to the rear of the edge of the blade, and is concentric with the tool. With this construction, the front edge of the blade may be ground or cut away to sharpen 35 the blade, or to remove the nicks formed therein by engagement with the tacks, and this grinding or cutting away of the front edge of the blade will not change the relation of the edge to the axis of the spindle, 40 or effect any change in the path of travel of the blades.

In the construction shown, the machine is provided with two work engaging guards arranged at opposite ends of the tack pulling blades 5, and so mounted that the tool 45 3 and the blades may be rapidly rotated while the guards remain stationary, or rotate independently of the tool and blades. In the form shown, these guards consist of 50 two disks 7 and 8 loosely mounted upon the reduced end 2 of the spindle, and arranged at opposite ends of the tool 3. The rims of the disks lie substantially in or 55 slightly within the plane of travel of the edges of the tack pulling blades. The blades of the tack pulling tool are preferably so formed that the periphery of the tool or plane of travel of the edges of the blade is substantially frusto-conical, the smaller diameter of the tool being toward the end of 60 the spindle. The periphery of the tool is also bowed or curved outward somewhat between the ends of the blades, as indicated, since this construction of blade is more efficient in passing beneath the head of the 65

tack when it is embedded in the surface of the sole. The frusto-conical construction and arrangement of the tool is also of advantage, since it enables the surface of the sole to be held in a horizontal position and 70 to be moved transversely of the axis of the tool when bringing the surface of the sole into the path of the tack pulling blades, and enables the shoe to be tipped laterally away from the spindle 1 in bringing the tack 75 into the path of the blades. The sole tacks may thus be brought into proper position to be acted upon by the tack pulling blades under all conditions without danger of interference by the engagement of some part 80 of the shoe with the spindle.

In utilizing the machine for pulling sole tacks, the sole of the shoe will be engaged with the guard 8 by the operator, and will be moved transversely to the axis of the 85 spindle until the tack which is to be pulled is in proper position with relation to the periphery of the rapidly revolving tool. During this movement, the guard 8 rotates about the reduced end of the spindle, and 90 rolls along the surface of the sole, so that the work may be easily and conveniently moved with little exertion on the part of the operator. When the operator has brought the tack into proper position to be 95 pulled, he tips the shoe on the guard 8, and in case the tack is driven way in, or has its head embedded in the sole, he continues the tipping movement until the surface of the sole rests against the guards 7 and 8, 100 and then presses the work against the guards, thus bringing the surface of the sole at the point where the tack is located into position where it intersects the path of travel of the blades 5. At this time the 105 guards 7 and 8 are stationary, and it is only necessary for the operator to hold the shoe against the action of the rotary blades as they operate upon the tack to wipe or pull it out of the sole. When this tack has been 110 extracted, the shoe is tipped to bring the surface of the sole out of the path of the tack pulling blades, and then the shoe is moved by the operator to bring the next tack into position to be extracted, the guard 8 rotating to facilitate the movement of the shoe.

While the machine shown and described is especially designed for use in pulling sole tacks, and its operation has been described with reference to such use, it will be understood that it may be used for pulling other tacks. It will also be understood that the features of the invention may be embodied in machines especially designed and intended for use in pulling tacks other than sole tacks, and that the specific construction and arrangement of the parts may be varied and modified without departing from the invention.

Having explained the nature and object of the invention, and specifically described one construction in which it may be embodied, what I claim is:—

5. 1. A tack pulling machine, having, in combination, a rotary tool provided with a tack pulling blade extending crosswise of its periphery and constructed to engage and pull tacks, and a work supporting guard 40
10 arranged at one end of the tool and mounted to permit rotation of the tool independently of the guard, substantially as described. 45
2. A tack pulling machine, having, in combination, a rotary tool provided with a tack pulling blade constructed to engage and pull tacks, and a relatively rotatable work supporting guard disks at opposite ends of the tool, substantially as described. 50
- 15 3. A tack pulling machine, having, in combination, a rotary tool provided with a tack pulling blade constructed to engage and pull tacks and a relatively rotatable guard mounted concentrically with and at one end of the tool, substantially as described. 55
- 20 4. A tack pulling machine, having, in combination, a rotary tool provided with a tack pulling blade constructed to engage and pull tacks, and two relatively rotatable guards mounted concentrically with and at opposite ends of the tool, substantially as described. 60
- 25 5. A tack pulling machine, having, in combination, a frusto-conical rotary tool 65
30 having a tack pulling blade extending crosswise of its periphery and constructed to engage and pull tacks, and a guard at the larger end of the tool, substantially as described. 70
- 35
6. A tack pulling machine, having, in combination, a frusto-conical tool having a tack pulling blade extending crosswise of its periphery and constructed to engage and pull tacks, and work supporting guard disks at opposite ends of the tool, substantially as described. 40
7. A tack pulling machine, having, in combination, a frusto-conical tool having a tack pulling blade extending crosswise of its periphery and constructed to engage and pull tacks, and relatively rotatable work supporting guard disks at opposite ends of the tool, substantially as described. 50
8. A tack pulling machine, having, in combination, a rotary tool having a tack pulling blade provided with a chisel edge adapted to dig under the head of a sole tack and a peripheral surface extending circumferentially to the rear of the edge concentric with the axis of the tool, and a work supporting guard at one end of the tool substantially in the plane of the path of travel of the edge of the blade, substantially as described. 55
9. A tack pulling machine, having, in combination, a tack pulling tool provided with a blade extending crosswise of its periphery and having a convex edge adapted to dig under the head of a sole tack, and a work supporting guard, substantially as described. 65

In testimony whereof I affix my signature, in presence of two witnesses.

JOHN B. HADAWAY.
